(57) **CLAIM**

The ornamental design for an UV lamp, as shown and described.

DESCRIPTION

FIG. 1 is a front perspective view of an UV lamp showing my new design;

FIG. 2 is a rear bottom perspective view thereof;

FIG. 3 is a front view thereof;

FIG. 4 is a rearview thereof;

FIG. 5 is a left view thereof;

FIG. 6 is a right view thereof;

FIG. 7 is a top view thereof; and,

FIG. 8 is a bottom view thereof.

The broken lines shown in the figures are for the purpose of illustrating portions of the UV lamp, which form no parts of the claimed design.
